(57) **CLAIM**

The ornamental design for a solid state drive memory device as shown and described.

DESCRIPTION

FIG. 1 is a front perspective view of a solid state drive memory device showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is another perspective view thereof.

The evenly dashed broken lines in the figures depict portions of the solid state drive memory device that form no part of the claimed design.
